Frederick W. Parker
ATTORNEY

Patented June 23, 1925.

UNITED STATES PATENT OFFICE.

HARRY S. WOLFF, OF NEW ROCHELLE, NEW YORK.

HOSE.

Application filed August 21, 1924. Serial No. 733,270.

To all whom it may concern:

Be it known that I, HARRY S. WOLFF, a citizen of the United States, residing at New Rochelle, in the county of Westchester 5 and State of New York, have invented certain new and useful Improvements in Hose, of which the following is a specification.

This invention relates to hosiery and my improvements are particularly directed to 10 hose intended to be worn next the skin, to supply warmth, and to serve as a base for more decorative outer hose drawn thereover.

Since my introduction in the market of 15 base or under hose, and the extensive use thereof that has ensued, some users have regarded the relatively heavy woolen material, of which these under hose are composed, added to the material of the silken hose placed thereover, as making too snug 20 the fit of the foot within the shoe, and leading to the necessity of wearing a larger sized shoe.

Therefore my present invention consists 25 in so devising the foot portion of a base or under hose that the toe and heel portions of the wearer's foot and the sole thereof under the instep will be left uncovered, while at the same time not detracting from 30 the snugly fitting quality of said foot portion upon the wearer's foot, nor causing it to present any loose edges liable to roll up and bunch when drawing the outer hose thereon.

Other features and advantages of my in- 35 vention will hereinafter appear.

In the drawing:

Figure 1 is a side elevation of my im- 40 proved hose displayed on a wearer's leg.

Fig. 2 is a similar view, the foot portion 45 of the hose being shown in vertical section.

Fig. 3 is a bottom plan view.

In said views the foot portion of the hose is shown as having the formed opening 1 at its toe end, said opening, whose edge may 50 be suitably hemmed or bound to prevent unravelling of the material, comprising the terminus of the hose, permitting the protrusion of the toes, or a part thereof, and being adapted to lie snugly against the toes.

This effect is produced by fashioning the 55 hose foot portion, as at 2, to accord that portion a substantially tapering or truncated cone-like contour, whereby the edge of opening 1 will bind against the toes. Said edge of opening 1 extends beyond the ball 60 of the foot and over what is known as the

"sesamoid" bone, which is the bone at the base of the toe. The reason for seeking and achieving this effect is that thereby the hose material at the opening 1 will not roll over and bunch up as an outer hose is drawn 60 over the foot.

From the drawings it can be seen that the toe portion of the hose extends to a point beyond the joint adjacent the ball of the foot and encircles the foot portion and a portion of the toe portion of the foot; or in other words, the toe portion of the hose extends to a point adjacent the toes, it being obvious from the particular positioning of the hose that the tendency of the hose to 70 slide upwardly or rearwardly on the foot and also the tendency of the edge of the hose to roll over is eliminated while the hose is in use.

It is to be understood that my improved 75 base or under hose is composed of wool or other relatively heavy material, to supply warmth, so that, for example, a silken hose may be placed thereon to supply the more decorative effect.

Also, it is to be understood that in practice my improved under hose is preferably 80 of flesh color, in order that silk or other hose of relatively diaphanous material will not have the appearance of their coloring 85 effect impaired by a base of contrasting color.

At the heel portion of the hose foot there is also provided an opening 3, whose edge 90 may be similarly hemmed or bound, and which permits the protrusion of the wearer's heel.

These openings 1 and 3, by exposing the wearer's toes and heel, enable the silk or outer hose to have direct contact therewith, and thus do not add the thickness of the base hose material to these portions of the foot. In consequence the wearer may use the same sized shoe as when only a silken hose is worn without experiencing the discomfort which might result if the added thickness of heavy weight under hose material were applied at the toe and heel.

Since pressure at the instep may also result from the imposition of under hose material in that region, this is compensated for in my improved hose by providing the sole opening 4, also suitably hemmed or bound, this opening occurring beneath the instep for that purpose.

It has hereinbefore been set forth that the

snugly fitting effect of the hose foot portion toward the toe opening is achieved by fashioning that portion to accord it a substantially tapering or truncated cone-like contour. By "fashioning" it is meant that the material at the foot base is provided with a central longitudinal seam 5, uniting the opposed edges which have been cut so as to convergently draw the material inwardly 10 and hold it snugly to the foot.

Variations within the spirit and scope of my invention are equally comprehended by the foregoing disclosure.

I claim:

- 15 1. Under hose including a foot portion having a fashioned forward end extending forwardly beyond the ball of the foot and over the sesamoid bone, said forward end being open at its extremity to permit projection of the toes, said forwardly extending end entirely surrounding the corresponding portion of the foot, the said forward end converging forwardly to hold the material snugly to the foot.
- 20 2. Under hose whose toe, heel and sole are provided with openings for the exposure of the wearer's foot respectively at its toe, heel and sole portions, the under hose being fashioned with tapering contour toward the 30 toe opening, to permit the peripheral edge

of said opening to lie snugly against the toe portion of the wearer's foot.

3. Under hose including a foot portion having a fashioned forward end extending forwardly beyond the ball of the foot and open at its extremity to permit projection of the toes, said forwardly extending end entirely surrounding the corresponding portion of the foot, and covering the same from the toes to the arch of the foot, the 40 heel portion of the hose being cut away to allow projection of the wearer's heel and prevent double thickness when wearing the under hose with other hosiery, the foot portion being also cut away beneath the instep 45 to relieve pressure at such point.

4. Under hose including a foot portion having a fashioned forward end extending forwardly beyond the ball of the foot and to a point adjacent the toes and open at its extremity to permit projection of the toes, said forwardly extending end entirely surrounding the corresponding portion of the foot, the said forward end having a central longitudinal seam and converging forwardly to draw the material inwardly and hold it snugly to the foot.

Executed this 11th day of August, 1924.

HARRY S. WOLFF,
